VACUUM CLEANER

Julius P. Wied, Cleveland Heights, Ohio, assignor
to The Apex Electrical Manufacturing Company, Cleveland, Ohio, a corporation of Ohio

Application November 25, 1949, Serial No. 129,385

9 Claims. (Cl. 183—37)

1

This invention relates to the separation of entrained matter from gas by the application of centrifugal and other forces to the gas and entrained matter, and more particularly to a vacuum cleaner embodying dirt separating means of this type.

In a co-pending application of Archibald H. Davis and Charles N. Hay, entitled "Dust Separator," Serial No. 788,850, filed November 29, 1947, now U. S. Patent 2,542,634 dated February 20, 1951, a dust separator operable by imparting a cyclonic action to dirt-laden air is disclosed as being embodied in a vacuum cleaner commonly referred to as the "upright" type, wherein the cleaner as a unit is propelled over a surface to be cleaned by a handle. The present invention relates to adapting a dust separator of the type disclosed in the aforesaid application to a vacuum cleaner of the type normally employing an extension hose and tubular wand to which floor cleaning and other tools are attached for cleaning purposes.

According to the invention, a dust separator which comprises a substantially cylindrical shell having one end portion converging inwardly to an end wall, a tangential inlet, and an axial outlet, is encased by a generally tubular housing forming a dust collecting receptacle. A motor and fan assembly is disposed beneath the separator and the air is normally discharged through silencing means. The parts forming the dust collecting receptacle may be easily and quickly removed for disposal of dust. Means are provided for protecting the motor from dust in the event that the receptacle becomes overloaded with dust through neglect in emptying the receptacle at proper intervals. An improved valve arrangement associated with the cleaner permits the extension hose to be quickly converted from a suction creating means to a blower means.

It is a primary object of the invention to embody a dust separator adapted to separate entrained matter from air by cyclonic action in a vacuum cleaner of the type having an extension hose adapted to have cleaning tools associated therewith for normal use.

Another object of the invention is to provide a vacuum cleaner of the above type having a dust collecting receptacle which can be quickly and easily detached for disposal of dust.

Another object of the invention is to provide a vacuum cleaner of the above type having a motor which is cooled by air passing from the separator and wherein means are provided for

2

protecting the motor from dust in the event the dust receptacle becomes overloaded.

Another object of the invention is to provide a vacuum cleaner of the above type having valve means associated therewith whereby the extension hose can be quickly converted from a suction creating means to a blower means.

Another object of the invention is to provide a vacuum cleaner of the above type having means for silencing or reducing the noise caused by discharge of air from the cleaner.

Other objects of the invention are to provide a vacuum cleaner of the above type having relatively few parts, which can be economically manufactured and assembled, and which is relatively compact.

Further objects of the invention and the invention itself will become increasingly apparent from a consideration of the following description and drawings, wherein:

Figure 1 is a vertical medial sectional view of a vacuum cleaner embodying the invention;

Figure 2 is a staggered transverse sectional view taken along the line 2—2 of Fig. 1;

Figure 3 is a plan view of the lower portion of the cleaner which houses the motor and fan assembly with parts broken away for clearness of illustration;

Figure 4 is a vertical sectional view of a valve means which I may employ, adjusted to create suction in an extension hose;

Figure 5 is a view generally similar to Fig. 4 with the valve means adjusted for blowing air through the extension hose;

Figure 6 is an end elevational view of closure means illustrated in Fig. 4 as viewed from a plane indicated at 6—6; and

Figure 7 is a vertical sectional view showing linkage for operating the closure means illustrated in Fig. 6.

Referring now to the drawings and particularly Fig. 1, I have indicated generally at 10 a dust separator which comprises a shell having a side wall which is slightly tapered for a major portion 45 of the shell length as indicated at 11, or this portion of the shell is in the form of a frusto-cone. The remaining portion of the side wall indicated at 12 converges inwardly along a curved path to join an end wall 13. This portion of the shell 50 conforms generally to an ellipsoid or the entire shell may be considered to substantially define a semi-ellipsoid. Extending upwardly from end wall 13 is an axially disposed tubular outlet 14 and a plurality of supporting legs 16 (preferably 55 4) extend downwardly from wall 13. An inlet

generally indicated at 17 merges tangentially with the arcuate portion 12 of the shell. The outlet 14 and inlet 17 are more fully disclosed and described in the aforesaid Patent No. 2,542,634 and only a brief description is given herein.

The lower portion of the cleaner housing consists of a generally cup form housing member 18 preferably formed of sheet metal. Member 18 has an annular ridge 19 formed in its base which supports a motor and fan assembly generally indicated at 21. The motor and fan assembly is of conventional construction wherein a high speed electric motor drives a fan encased in a housing provided with a plurality of circumferentially spaced slots 22 through which air is discharged and diffused. Air passing from the separator is used to cool the motor and passes interiorly of the motor housing in reaching the fan. Thus, the cooling air must be substantially free of dust to avoid injury to the motor parts and the means by which this is effected will be explained in detail hereafter. The assembly 21 is cushioned by mounting the same on rubber or the like tubes 23 which are secured by projecting screws 24 through ridge 19 and the tubes to threadedly engage the fan housing. Screws 24 also secure a ring form element 26, preferably formed of sheet metal, to member 18.

Element 26 has an inturned top flange which supports a generally disc shaped member 27, member 27 being detachably secured to element 26 by screws 28. The peripheral edge of member 27 is encased by a rubber ring 29 which engages the interior wall of cup member 18 to provide an effective seal at this zone. The central portion of disc member 27 is of inverted cup form as indicated at 31 and the side walls of portion 31 are pressed outwardly at circumferentially spaced points to provide openings 32. The pressed out parts of the side wall provide horizontally extending short flanges 33 which help support a ring form filter element 34. Disc member 27 is formed to provide an annular shoulder 36 which supports the outer portion of filter element 34. The filter element may be formed of any suitable material which will filter out dust and permit the passage of air therethrough, but I preferably employ felt or the like material. A rubber ring 35 forms a seal between the motor housing and disc member 27.

It will be noted that an annular passage 37 is formed between the side walls of cup member 18 and element 26 and a ring of glass wool or the like material indicated at 38 is disposed in the upper portion of the passage. Above ring 38 the side walls of cup member 18 are pressed outwardly at circumferentially spaced points to provide a plurality of discharge openings 39. From a standpoint of appearance I preferably encase the flanges formed in providing the openings 39 with a ring of rubber or the like as indicated at 41.

It will also be noted that the base of cup member 18 including ridge 19, the element 26, the disc member 27, and rubber ring 35 form a chamber 40 encasing the fan diffuser slots 22.

The dust separator 10 is supported by the spaced legs 16 which rest on the central portion 31 of disc member 27 and the separator is held in fixed position by the inlet 17 which extends through the side wall of cup member 18. The upper end of the separator is formed with an external annular shoulder 42 to which is bonded a sealing ring 43 formed of suitable material

such as rubber. The side wall of cup member 18 at its upper end is of step form to provide an annular shoulder forming a seat for a sealing ring 44. The sealing rings 43 and 44 support parts forming a dust collecting receptacle indicated at 46. The dust collecting receptacle comprises a ring member 47 generally U shaped in cross section, the inner wall of the ring member having a top inturned flange 48 adapted to sealingly abut rubber ring 43. Although I preferably bond or secure ring 43 to shoulder 42 of the separator, it is understood that it may be secured to flange 48 of ring member 47. I preferably form the ring member in two parts and of plastic material such as a plastic formed of a styrene resin. The part indicated at 49 is generally cylindrical and is formed of a transparent plastic while the remainder of ring 47 is formed of an opaque plastic and the plastic materials are bonded together along the joint indicated at 51. Since the ring 47 is adapted to collect dust, the part 49 serves as a window indicating the dust level. Of course, the entire receptacle could be made of transparent material, but the opaque material hides the parts disposed beneath the receptacle from view. A cover 52 preferably formed of plastic material, is provided with a peripheral groove within which a sealing ring 53 is secured, the groove being adapted to receive the top edge of part 49 which abuts ring 53 in sealing relation. Conventional snap clamps 54 detachably lock cover 52 to ring 47 and detachably lock ring 47 to cup member 18.

The central top portion of cover 52 is depressed to provide a conical baffle 56 which projects within the shell of separator 10 and the baffle terminates in a vertically extending and slightly tapered side wall 57 to provide an annular opening 58 between the separator wall portions 11 and the wall 57. A handle 59 which has its ends secured to wall 57 is provided for grasping the cover or for carrying the dust collecting receptacle comprising the ring 47 and the cover 52.

The operation of the parts so far described will now be explained. Electrical leads extend from the motor to a terminal block 61 and thence to a conventional socket 62 mounted in the side wall of cup member 18. Although not illustrated, a switch to control the motor circuit may be used if desired. Upon connecting an extension cord plugged into socket 62 with a power source, the motor and fan will be actuated. Dirt-laden air will be drawn into inlet 17 and directed to the interior of the separator shell. Since the air strikes wall portion 12 generally tangentially it will have a whirling action imparted thereto and at the same time, due to the curvature of wall portion 12 or its gradual divergence outwardly as it proceeds upwardly to merge with tapered wall portion 11, the air is also directed upwardly. Thus, the dirt-laden air is first caused to move in a generally helical or cyclonic path proceeding upwardly. The relatively heavy dust or dirt particles are thrown by centrifugal force against the interior wall of the separator shell and due to the upward movement are carried through the annular opening 58 and deposited in the receptacle 46. Due to the combined effect of the baffle 56 and the suction created by the fan in outlet 14 the air is then directed downwardly while continuing its whirling motion in the same direction. Thus, the air is caused to move upwardly in an outer cyclonic path and downwardly in an inner cyclonic path but relatively greater

centrifugal force is applied to any dust particles in the inner path due to the sharper change of direction of the particles and the increased speed caused by moving a given volume of air along a path of reduced circumferential extent in a given interval. Relatively light particles will thus be thrown into or through the outer cyclonic path and carried upwardly along the shell wall through opening 58. The separation of entrained dust particles from air in this manner is more fully explained in the aforesaid Patent No. 2,542,634.

The cleaned air will then pass through outlet 14, between legs 16, through filter element 34, through openings 32, interiorly of the motor housing to cool the motor, through the fan, and will be discharged through diffuser slots 22 into the chamber 40. I provide an outlet tube 63 having a normally open mouth 64, the tube passing through the wall of element 26 and discharging into passage 37. Tube 63 is generally rectangular in cross section inwardly of element 26 and upon entering chamber 37 the bottom wall of the tube is cut away so that the portion of the tube extending between element 26 and the side wall of cup member 18 is of inverted U form. It will be noted by reference to Fig. 1 that the bottom edges of the tube side walls extend somewhat below the bottom of ring 38. The ring abuts the tube side walls so that air passing through tube 63 will be discharged beneath the ring and distributed circumferentially around passage 37. The air will then pass upwardly through the ring material and be discharged to atmosphere through the circumferentially spaced openings 39.

I have found that by passing the air through a relatively large mass of glass wool, steel wool, rock wool, or the like, and then discharging the air through a plurality of small ports, that the objectionable whistling or hissing noise attendant upon the discharge of air through a single port in a conventional cylinder type cleaner is deadened or substantially reduced.

It will be noted by reference to Fig. 1 that I have provided slots 66 in the upper portion of ring 47 which are covered by a screen 67. The slots are preferably equally spaced circumferentially and are elongate in a vertical direction. The screen is shown as disposed internally of ring 47 but may be disposed externally thereof and bonded or otherwise suitably secured to the ring. The purpose of the slots or vents 66 will now be described. A certain amount of whirling air is discharged or forced into receptacle 46 and serves as a vehicle for carrying dust into the receptacle. However, if this moving air cannot escape it creates turbulence and disturbs the dust already collected in the receptacle thereby tending to carry collected dust back into the separator shell. To avoid this condition I have provided the slots 66 whereby air entering receptacle 46 is drawn through the slots into the space formed by the external wall of the shell and the internal wall of ring 47. Since this space is subjected to suction created by the fan, this air is drawn through the motor and discharged to atmosphere as previously described. The screen 67 insures that only clean air contacts the motor and avoids clogging of the filter element 34.

As previously explained, part 49 of ring 47 is preferably transparent so that an operator of the cleaner may see the dust level and empty the receptacle when required. However, in the event the dust is permitted to reach a level defined by the top of ring 47, it is apparent that

additional dust will not be accommodated by receptacle 46. Accordingly, if the cleaner continues to operate under these conditions the dust will remain in the separator shell and be drawn through the outlet 14. Since dirt-laden air would quickly damage the motor, I provide the filter element 34 as a safety device, preventing dirt-laden air from reaching the motor under these conditions.

In the event the filter element 34 should become clogged or require replacement for any reason, this can be easily effected, since the separator shell and the inlet 17 integrally connected therewith may be rocked about the point of connection of inlet 17 with the side wall of cup member 18. As best illustrated in Fig. 4, I provide a metal ring 68 which abuts the inner surface of the side wall of cup member 18 and is secured thereto by screws 69. The side wall of member 18 is perforated to provide an opening for the passage of incoming dirt-laden air and ring 68 is aligned with this opening. Screws 69 project through the side wall of member 18 and threadedly engage a valve device generally indicated at 71. A sealing ring 72 is bonded or otherwise secured to the inner surface of ring 68. Tubular inlet 17 may be hinged to the side wall of cup member 18 in any suitable manner, but I preferably weld a pair of L-shaped arms 73 thereto, one being disposed at each side of the inlet. A pair of ears 74 are fixed to the side wall of cup member 18 and a pin 76 projects through the ears and arms thereby forming a pivotal connection. If it is desired to remove or replace filter element 34, the receptacle 46 and cover 52 are removed and the shell and tubular inlet 17 are rocked counterclockwise (Fig. 1) about pin 76 as an axis which will lift legs 16 out of contact with central portion 31 of disc member 27 and permit filter element 34 to be removed and replaced by a new element.

In the event it is only desired to use the cleaner for creating suction, the screws 69 may affix a tubular element to the external surface of the side wall of cup member 18 and this element will have its external or outer end adapted to receive a conventional coupling associated with an extension hose. The hose will normally include a metal wand adapted to have cleaning tools attached thereto whereby suction will be created at the tools and dirt-laden air will be drawn through the tools, the extension hose, and the entrained dirt will be separated from the air in the manner previously described.

Although a cleaner of this type will normally function as a suction device, it is desirable that it be adaptable to also function as a blower device whereby it can be utilized in a conventional manner for spraying paint, demotching, and the like. To achieve this dual function, I have provided a simple valve arrangement whereby the air normally exhausted to atmosphere through the openings 39 will be directed through an outlet or blower port. As best illustrated in Figs. 4 to 7 inclusive, the valve arrangement comprises a casting having an upper tubular portion 77 which is secured to the side wall of cup member 18 by screws 69. Integrally joined to tubular portion 77 is a lower tubular portion 78 which projects through aligned openings formed in the side wall of cup member 18 and element 26. A vertically extending rib 79 connecting the tubular portions is formed with a boss 81 within which a pin 82 is press-fitted. Pin 82 supports a rotatable converter element generally indicated at 83. The

converter element comprises the tubular portion 84, a bearing portion 86 which engages pin 82 and an arm 87 which is provided with horizontally-extending slots as indicated at 88. A compression spring 89 abuts the outer face of rib 79 and the inner face of arm 87 and tends to hold the converter element 83 spaced from the casting.

Pin 82 is headed at one end and slotted at its opposite end. A latch handle 90 has an end portion projected within the slotted end of pin 82 and pivotally connected thereto by a pin 91. Rib 79 has a lug 92 projecting therefrom and converter element 83 has a similar lug 93 whereby when the parts are in the position illustrated in Fig. 4, the lugs will abut to align the tubular portions 77 and 84. When the handle 90 is rotated downwardly the inner edge thereof will cam the element 83 into engagement with the casting against the force of spring 89. To effect a tight seal between tubular portions 77 and 84, a rubber gasket 85 is bonded to the end face of tubular portion 84. The outer end of tubular portion 84 is adapted to engage an extension hose (not shown) through suitable coupling means. Coupling means of the type contemplated are well known and may be of the bayonet type whereby a pin projecting from tubular portion 84 would engage an L-shaped slot in a coupling member associated with the hose to sealingly lock the hose to portion 84.

With the valve parts adjusted as described, dirt-laden air drawn through the hose is discharged to atmosphere as clean air through the openings 39. To prevent discharge of air through lower tubular portion 78 I provide a closure plate 94 generally rectangular in form and which is hinged along one edge by a pin 96 which projects through cooperating lugs formed on the plate and the inner end of portion 78. A spring 97 has one end fixed to portion 78 and its opposite end fixed to plate 94 and tends to hold the plate in sealing engagement with the inner end of portion 78. Under these conditions the mouth 64 of outlet tube 63 is open.

When it is desired to use the extension hose as a blowing means with a paint spraying attachment or the like, this is quickly accomplished by merely releasing the latch handle 90 or lifting it to the position illustrated in Fig. 4, rotating the element 83 through 180° to the position illustrated in Fig. 5, and rotating the handle 90 upwardly into locking position. The lug 92 is adapted to abut an inner wall of handle 90 to align tubular portions 84 and 78. This connects the extension hose with the lower tubular portion 78. The locking movement also forces closure plate 94 out of sealing contact with the inner end of portion 78 and into sealing contact with mouth 64 of tube 63. This is effected in the following manner. The inner end of portion 78 is slotted as indicated at 98 to receive an end portion of lever 99 which projects between a pair of lugs 101 integral with portion 78 and is pivotally connected to the lugs by a pin 102. A rod 103 has a down-turned end which projects through a hole in lever 99. The opposite end of the rod is slidably supported by a lug 104 formed on the inner wall of portion 78 and through which rod 103 projects and when closure plate 94 is in sealing contact with portion 78, as illustrated in Fig. 4, lever 99 is entirely within portion 78 and extends cross-wise thereof. The straight end of rod 103 then extends somewhat beyond portion 78 as illustrated in Fig. 7. When tubular portions 84 and 78 are brought into engagement a pad 106 on the inner wall of portion 84 engages the end of rod 103 and forces the rod 75

to the right or the dotted line position illustrated in Fig. 7. Since the rod is hooked to lever 99 the free end of the lever is forced outwardly and at an angle to the end face of portion 78 as illustrated in Fig. 3. This movement of the lever is sufficient to push closure plate 94 into sealing contact with the obliquely cut mouth 64 of tube 63. I preferably form plate 94 of relatively soft material such as aluminum, and to avoid undue wear, a pad 107 of hard metal is fixed to plate 94 at a position to engage lever 99.

When tube 63 is sealed, air cannot enter chamber 37 to be discharged to atmosphere, but instead is directed to portion 78 and the extension hose as a stream under positive pressure. If the valve is again adjusted to the position of Fig. 4, the plate 94 under the influence of spring 97 automatically seals portion 78 and leaves tube 63 open for the discharge of air into passage 37. When the cleaner is being used as a blower, air is drawn into inlet 17 through the horizontal slots 88 provided in arm 87.

In the event it is only desired to use the cleaner as a suction device certain parts can be omitted for economy. For example, the converter valve arrangement would not be necessary and inlet 17 would project through the side wall of cup member 18 and be adapted to directly connect with an extension hose. The casting, including tubular portion 78 and the parts supported by the casting would be omitted. Outlet tube 63 could be omitted and instead of a continuous ridge 19 spaced support pads for rubber tubes 23 could be provided whereby air issuing from diffuser slots 22 would pass under ring element 26 into passage 37 and then be discharged to atmosphere through openings 39.

Although I preferably employ the converter element 83 I contemplate that this part may be omitted whereby an extension hose would be directly coupled to the inlet or tubular portion 77 and to the blower tube or tubular portion 78. In this case the rod 103 would be designed to be engaged by the hose coupling and forced inwardly when the hose is coupled to the blower tube thereby closing tube mouth 64 by plate 94 and effecting communication between chamber 40 and the blower tube.

I find that by providing a slight taper to side wall 11 of the separator shell removal of dirt is improved relative to a straight or cylindrical side wall.

It will now be understood that I have provided a vacuum cleaner of the extension hose type adapted to separate dust or dirt from air by cyclonic action and wherein the dust is collected in a receptacle which can be quickly and easily detached from the cleaner for disposing of the dust. Also, the receptacle cover can be quickly detached. Since the dust receptacle has a smooth interior it is relatively easy to empty dust therefrom compared to a fabric bag used in a conventional vacuum cleaner. Also, I have provided means for silencing or minimizing the operable noise caused by discharge of air in a conventional cleaner. Further, the valve arrangement described permits the cleaner to be quickly converted from a suction device to a blower device.

I wish it to be understood that I do not desire to be limited to the exact details of construction shown and described, for obvious modifications will occur to a person skilled in the art.

What I claim is:

1. A vacuum cleaner comprising a separator

shell of generally semi-ellipsoid form having an upwardly open large end, a tubular inlet adjacent the small end of the shell and extending generally tangentially thereto for directing dirt-laden air into the shell, an axial tubular outlet within the shell and extending from the small end thereof adapted to direct air from the separator shell, a dirt storage receptacle comprising a ring of U form cross section encircling the separator, and means for detachably securing the receptacle to the cleaner.

2. A vacuum cleaner comprising a separator shell of generally semi-ellipsoid form having an upwardly open large end, a tubular inlet adjacent the small end of the shell and extending generally tangentially thereto for directing dirt-laden air into the shell, an axial tubular outlet within the shell and extending from the small end thereof adapted to direct air from the separator shell, a dirt storage receptacle comprising a ring of U form cross section encircling the separator, and a detachable cover for the receptacle having a central baffle portion adapted to project into the upper open end of the separator to provide an annular opening between the separator upper wall and said portion.

3. The vacuum cleaner as described in claim 2 and wherein the baffle portion of the cover is of conical form and terminates in a circular up-standing wall substantially parallel to the upper side wall of the separator.

4. The vacuum cleaner as described in claim 1 and wherein the inner wall of the receptacle ring sealingly engages the open end of the shell and is spaced from the shell wall proceeding downwardly from the open end to leave an annular space intermediate said inner and shell walls, said inner wall having an opening therein effecting communication between the receptacle and said space, and a filter screen covering said opening.

5. The combination with a vacuum cleaner having an inlet for dirt-laden air, a fan, means forming a chamber encasing the fan, a tubular outlet effecting communication between said chamber and atmosphere, and a blower tube extending from the chamber through a wall of the cleaner, of means adapted to convert the cleaner from a suction device to a blower device, said means comprising a rotatable element pivoted on the cleaner and having a tubular portion adapted to be connected to an extension hose, the tubular portion in one position being adapted to sealingly communicate with the inlet and in another position being adapted to sealingly communicate with the blower tube, means for locking the rotatable element in either position, a common valve means for the tubular outlet and blower tube, and means extending between the rotary element and valve means whereby when the tubular portion is locked in communication with the inlet the valve means will close the blower tube and when said tubular portion is locked in communication with the blower tube the valve means will close the tubular outlet.

6. In a vacuum cleaner, a fan, means forming a chamber encircling the fan adapted to receive air delivered by the fan, communicating means between the chamber and atmosphere, an inlet for dirt-laden air adapted to have an extension hose coupled thereto, a blower tube extending from the chamber to atmosphere, a closure normally sealing the chamber end of the blower tube,

means extending from the closure to the opposite end of the blower tube adapted upon being forced inwardly to move the closure from the blower tube to a position sealing the communicating means, and the extending means being adapted for engagement with an extension hose coupling whereby said means will be forced inwardly to effect sealing of the communicating means when an extension hose is coupled to the blower tube.

7. A vacuum cleaner comprising a separator shell of generally semi-ellipsoid form having an upwardly open large end, a tubular inlet adjacent the small end of the shell and extending generally tangentially thereto for directing dirt-laden air into the shell, an axial tubular outlet within the shell and extending from the small end thereof adapted to direct air from the separator shell, a dirt receptacle comprising a ring of U form cross section encircling the separator, means for detachably securing the receptacle to the cleaner, the inner wall of the receptacle ring being adapted to sealingly engage the open end of the shell, said ring inner wall being spaced from the shell wall proceeding downwardly from the open end thereof to leave an annular space intermediate said inner and shell walls, said ring inner wall having an opening therein effecting communication between the receptacle and said space, and a filter screen covering said opening.

8. A vacuum cleaner comprising a separator shell of circular cross section having a curved lower side wall portion terminating in a substantially flat base, the upper side wall portion being straight and terminating in an upwardly open end, the shell progressively increasing in cross sectional area from the base to the open end, a tubular inlet adjacent the base and extending tangentially of the shell for directing dirt-laden air into the shell, an axial tubular outlet extending into the shell from the base and adapted to direct air from the shell, a dirt storage receptacle comprising a ring of U form cross section encircling the separator, and means for detachably securing the receptacle to the cleaner.

9. The vacuum cleaner as described in claim 7 and wherein the radially inner wall of the receptacle is of a diameter to be telescoped over the upper end of a shell whereby the receptacle can be lifted upwardly for removal from the cleaner, and sealing means are provided between the upper end of the receptacle and shell.
